FIRING INDICATOR FOR INTERNAL COMBUSTION ENGINES

Filed July 7, 1932

UNITED STATES PATENT OFFICE

1,990,835

FIRING INDICATOR FOR INTERNAL
COMBUSTION ENGINESMurdock McLeod and John Allan, Winnipeg,
Manitoba, Canada

Application July 7, 1932, Serial No. 621,180

1 Claim. (CL 175—183)

The invention relates to improvements in firing indicators for internal combustion engines and an object of the invention is to provide an indicator on the dash or other prominent location of an automobile which will show visibly to the driver the condition of the spark plugs of the engine and indicate also definitely what spark plugs require attention.

A further object of the invention is to arrange the device so that under normal driving conditions, it is not in use and such that when the driver finds that his engine is not functioning properly, he can test the spark plugs by actuating a finger piece provided and when such is done, the indicator will show on the dash what plugs are not functioning properly and the exact location of such plugs.

A further object is to construct the entire device in a simple, durable and compact manner and so that it can be sold at comparatively small cost and introduced as part of the standard equipment of an automobile.

With the above more important and other minor objects in view which will become more apparent as the description proceeds, the invention consists essentially in the arrangement and construction of parts hereinafter more particularly described, reference being had to the accompanying drawing, in which:—

Fig. 1 is a perspective view of the device and showing the various electrical connections.

Fig. 2 is a perspective view of a portion of the dash.

Fig. 3 is an enlarged detailed horizontal sectional view at 3—3 Figure 2.

Fig. 4 is a vertical sectional view at 4—4 Figure 3.

Fig. 5 is an enlarged detailed vertical sectional view through the type of spark plug employed.

Fig. 6 is an enlarged detailed vertical sectional view through the upper end of the spark plug and showing the push pull connections used for the wires.

Fig. 7 is an enlarged detailed horizontal sectional view at 7—7 Figure 5.

Fig. 8 is a view showing the wiring diagram.

In the drawing like characters of reference indicate corresponding parts in the several figures.

The engine of the automobile is indicated generally by the reference numeral 1 and may have any number of cylinders, it being simply a matter of duplicating certain parts of our invention to accommodate the number of cyl-

inders. The engine shown is a four cylinder engine and is accordingly equipped with four similar spark plugs 2, 3, 4 and 5. These spark plugs are screwed into the engine head in the usual manner and are for the greater part of ordinary construction as will be apparent from an inspection of Figure 5 where it will be observed that the porcelain body 6 has the lower end received within the customary shell 7 and held therein by the bushing 8.

The porcelain body has the upper end thereof projecting above the bushing and provided at diametrically opposite sides with vertical channels 9 and 10, the lower ends of which terminate just above the bushing in horizontal faces to engage lock nuts later described. Through the body of the porcelain, we pass two electrodes 11 and 12 which have their lower ends inturned but spaced to provide a gap across which the usual firing spark jumps.

The upper end of the electrodes are provided within the channels 9 and 10 with extensions 13 and 14 of lesser diameter than the lower ends and the electrodes are held in place by bottom collars 15 secured to the electrodes and engaging the lower end of the porcelain and by top nuts 16 screw threaded onto the electrodes and engaging the lower closed ends of the channels.

The upper extensions of the electrodes are received within insulating ribs 17 and 18 contained within the channels and formed as part of an insulating cap 19 which encloses the upper end of the porcelain. The cap is provided at its upper end with two pockets 20 and 21 into which the upper ends of the extensions of the electrodes pass and the extension 13 of the electrode 11 has its upper end screw threaded into a metallic sleeve 22 contained within an insulating sleeve 23 received within the pocket 20. The pocket 21 contains also an insulating sleeve 24

and this carries two internally screw threaded socket like members 25 and 26 which have their inner ends spaced apart to provide a spark gap 27. The lower socket member receives the upper screw threaded end of the extension 14 of the electrode 12. Spring contacts 28 and 29 are screw threaded one into the upper end of the sleeve 22 and the other into the upper socket 26 and these spring contacts present each a pair of opposing spring jaws adapted to receive a ball 30 formed at the ends of the wires leading to the electrodes. It will be observed that the upper ends of the insulating sleeves surround the spring contacts.

According to the construction of the spark

plug just described, it will be apparent that there are two electrodes carried by the porcelain and that the main spark for firing the explosive mixture in the engine cylinder occurs between the lower ends of the electrodes and that this is intensified by the gap provided at 27, it being of course understood that the electric wires lead to and from the upper ends of the electrodes. Usually there is only one wire leading to each spark plug as one of the electrodes thereof is grounded to the engine. In our case, however, both electrodes are insulated from the engine.

The customary distributor is indicated by the reference numeral 31 and from this distributor, 15 four wires, indicated generally by the reference numeral 32, lead to the electrodes 12 of the spark plugs. Further wires 33 lead from the electrodes 11 of the spark plugs to the dash and there connect with a special device shortly described and from this device, further wires 34 lead back and 20 are grounded to the engine. The device provided on the dash is now described in detail.

A casing 35 is provided, the casing being suitably fastened to the dash and being provided with a front glass 36 and with a closure plate 37 of insulating material. Within the casing between the glass and plate, we insert a further relatively thick strip of insulating material 38 which is slotted to provide four closed compartments 39 visible through the glass or window. 30 In one end of the casing, we screw thread a sleeve 40 which is provided with a finger and thumb piece 41. A rod 42 extends lengthwise of the casing and centrally crosses the several compartments, the rod having the one end squared as indicated at 42' and received within a complementary squared aperture provided in the end of the casing to prevent rotation of the same and the other end rotatably received within the sleeve and provided with a circum- 35 scribing rib 43 rotatable within the sleeve.

According to this arrangement, when one turns the finger piece, the sleeve screws in or out in respect to the casing and as it moves, it carries the rod with it but the rod is prevented from turning due to the square end 42' and its squared receiving aperture. On the rod and more or less centrally within each compartment, we mount similar insulating sleeves 44 and these sleeves carry similar contacts 45. The wires 34 are 45 connected with the respective contacts 45.

Similar contacts 46 are suitably stationarily mounted within the compartments being carried by the closure strip 37 and these contacts are connected respectively to the wires 33 which 55 lead to the electrodes 11 of the several spark plugs.

Under normal operating conditions, the contacts 45 and 46 will be engaged but should the

driver at any time think that his engine is not firing properly due to possible trouble in the spark plugs, he will turn the thumb piece in a direction which will withdraw the contacts 45 away from those 46 thereby providing four gaps, one for each spark plug. By observing the different compartments through the window, he can immediately tell if one or more of the spark plugs are not functioning. This being determined, such plug or plugs can be examined and 10 repaired or replaced with new ones.

It is desirable to have the wiring arranged so that immediately a faulty spark plug is detected by the absence of a spark or the observing of a poor spark in any compartment, the driver will know the exact spark plug which is not operating. This can be readily done by always considering the front spark plug of the engine as number one and those following as two, three and four and then connecting the 15 wires to the indicator and numbering the compartment in an order such that when say compartment two indicates trouble, that trouble will be found at the second spark plug of the engine numbering from the front and so on with 20 the others.

While we have entered into a detailed description of the various parts, it will be understood that they could be readily modified without departing from the spirit of the invention 25 as set forth in the appended claim.

It will be noted that the gaps 27 are between the wires 32 leading from the distributor and the electrodes 12 of the spark plugs so that the firing spark produced by the plug is intensified. 30

What we claim as our invention is:—

In a firing indicator for internal combustion engines, a prominently mounted casing provided with a sight glass, an insulating member mounted within the casing and provided with a plurality of separate compartments visible through the sight glass, a stationary contact in each compartment carried by the member, a non-rotatable, endwise slidably, rod carried by the member and crossing the several compartments, said rod being journaled at one end in a rotary thumb piece located exteriorly of the casing and slidably and non-rotatably squared at the other end of said casing to effect the endwise shifting of the rod upon the rotary movement of the thumb piece, a contact member located in the compartment and movable with the rod but insulated therefrom, said stationary contact and movable contact being oppositely opposed and spaced to provide spark gaps. 40 45 50 55
